UNITED STATES PATENT OFFICE.

WILLIAM FETH, OF LIMA, OHIO.

MOP HOLDER.

Application filed September 25, 1922. Serial No. 590,409.

To all whom it may concern:

Be it known that I, WILLIAM FETH, a citizen of the United States, and a resident of Lima, in the county of Allen and State 5 of Ohio, have invented certain new and useful Improvements in Mop Holders, of which the following is a full, clear, and exact description.

My invention relates to a mop holder so 10 constructed that the mops may be quickly and easily changed. In attaching and removing mops considerable trouble is often involved, due to the mop becoming entangled with parts of the holder. In my construction one end of the holder is thrown 15 entirely open so that there is a wide, free passage for the removal or insertion of the mop without any parts about which the mop strings might tangle.

Another object of my invention resides 20 in the provision of a mop holder which will have the rapid-change feature and yet will not have its strength or durability lessened.

Another object of the invention is to provide 25 a mop holder of this character which has a new and improved means for locking the movable arm to the body of the holder.

A further advantage of the invention is 30 that all corners and edges of the holder are rounded, so that the woodwork, etc., will not be scratched in the operation of the mop.

Further, the holder is so constructed that 35 in the event of breakage of any part of the holder that part may be easily replaced, thus obviating the necessity of discarding a holder because of breakage of one of its elements.

Still another object of the invention is 40 to provide a holder of this character which is most simple in construction, inexpensive in manufacture, and which is strong and durable in operation.

Other and further objects and advantages 45 of the invention will be apparent from the following detailed description when taken in connection with the accompanying drawings, in which:

Figure 1 is an elevation of the mop 50 holder, the handle portion being broken away, and the movable arm being shown in dotted lines in open position.

Figure 2 is a transverse horizontal sectional view taken on line 2-2 of Fig. 1.

55 Figure 3 is a vertical transverse sectional view taken on line 3-3 of Fig. 1; and

Figure 4 is a detail view, showing the interlocking means.

Referring to the drawings more in detail, numeral 1 indicates the handle portion, which is of the usual construction, and has attached thereto the ferrule 2. This ferrule is formed in two similar sections, and each section has outwardly extending wings 3, 3, between which the arms 4 and 5 are secured. The arm 4, which is rigidly attached to the ferrule by a plurality of rivets, has a general U shape, comprising an inclined portion, a downwardly extending portion, and a transverse extension or crossbar 6. The arm 5 is pivotally attached to the ferrule, as by means of a rivet, so that this arm is adapted to swing laterally. The two arms are arranged to engage and interlock in a manner to be described hereinafter.

A screw threaded rod 7 passes through a suitable opening in the bottom of the ferrule, and this rod is secured to the ferrule and held stationary with respect thereto by the lock nut 8. A wing nut 9 is screw threadedly mounted on the rod 7, and this nut operates against a follower 10 which is slidably mounted on the rod.

The follower 10 may be of any preferred 85 construction, but in the form illustrated it includes a sleeve 11 adapted to receive the rod 7, and extending from the sleeve are the spacing plates 12, 12, which reach to the frame of the holder. Plates 13, 13 are riveted or otherwise attached to the spacing plates and extend slightly beyond the spacing plates, thereby forming a guideway for the reception of the arms 4 and 5. The plates 13 are preferably provided with outwardly curved flanges 14 for engaging and pressing the mop against the transverse extension or crossbar 6.

The means for interlocking the crossbar 6 and the movable arm 5 will now be described.

The end of the crossbar is inclined, as indicated by the numeral 15, and is provided with a notch 16 adjacent the inclined edge. The movable arm 5 is slightly offset adjacent the lower arm, as indicated by numeral 17, and the lower end of the arm is bent upwardly to form a hook 18; and riveted or otherwise secured to the hook thus formed is a transversely extending pin 19.

The material of which the arms are made will possess some resiliency, and when the

movable arm 5 is swung to the left (Fig. 1) the cross arm 6 will spring slightly outwardly to a position substantially as shown in dotted lines in Fig. 1. To secure a mop 5 in place it is only necessary to position it on the crossbar 6, then swing the movable arm inwardly, and when the pin strikes the inclined end of the crossbar it will draw the latter inwardly until the notch 16 is reached, 10 whereupon the pin will ride into the notch and securely interlock the crossbar and movable arm. To clamp the mop into position it is only necessary to set up on the wing nut 9. To remove a mop the operation 15 is just the reverse, by pressing inwardly on the crossbar 6 the notch will be disengaged from the pin 19, permitting the movable arm 5 to swing outwardly, thereby providing a broad and free passage for the removal of the mop.

From the foregoing description it is apparent that my mop may be changed quickly and easily, and also that no obstructions are presented for the entanglement of the threads 25 of the mops.

It is also apparent that, while I have provided this rapid-change feature, I have not in any way weakened the structure. And in this connection it is to be noted that I 30 preferably employ pressed flat stock, which will resist bending or twisting to a much greater extent than round stock, or wire.

The holder described above is most simple in construction, inexpensive in manufacture, 35 durable in operation, and neat and attractive in appearance.

In accordance with the patent statutes, I have described what I now believe to be the best embodiment of the invention, but I do 40 not wish to be understood thereby as limiting myself or the scope of the invention, as many changes and modifications may be made without departing from the spirit of the invention; all such I aim to include in 45 the scope of the appended claims.

Having fully described my invention, what I claim as new and desire to secure by Letters Patent is:

1. A mop holder, including a fixed arm 50 and a movable arm, the fixed arm carrying an integral resilient crossbar, and the movable arm and crossbar provided with co-operating means whereby they are interlocked when brought into co-operating position.

2. A mop holder, including a fixed arm 55 and a movable arm, the fixed arm carrying an integral crossbar, the crossbar provided with a notch adjacent its end, and

the movable arm provided with means for 60 engaging in said notch.

3. A mop holder, including a fixed arm and a movable arm, the fixed arm carrying a crossbar, the end of said crossbar being inclined, and means carried by the movable 65 arm to engage said inclined end and draw the crossbar inwardly, and means on the fixed arm for detachably engaging the first mentioned means.

4. A mop holder, including a fixed arm 70 and a movable arm, the fixed arm carrying a crossbar, said crossbar having an inclined end and provided with a notch, and a pin carried by the movable arm for engaging the inclined end to draw the crossbar inwardly and for engaging the notch to interlock the crossbar and movable arm.

5. A mop holder, including a fixed arm and a movable arm, the fixed arm carrying a crossbar, said crossbar having an inclined 80 end and provided with a notch, said movable arm provided with a hook, a pin carried by said hook, said pin adapted to engage the inclined end to draw the crossbar inwardly and also adapted to engage the notch to 85 interlock the crossbar and movable arm.

6. A mop holder, including a handle and a ferrule mounted thereon, said ferrule provided with an opening, a screw threaded rod extending through said opening and secured 90 to the ferrule by a lock nut, a frame mounted on the ferrule and including a fixed arm and a movable arm, a crossbar carried by the fixed arm, co-operating means carried by the crossbar and movable arm for interlocking 95 them, a follower mounted on the rod, means screw threadedly engaging the rod for moving the follower toward the crossbar to engage a mop therebetween.

7. A mop holder, including a handle and 100 a ferrule mounted thereon, said ferrule provided with an opening, a screw threaded rod extending through said opening and secured to the ferrule by a lock nut, a frame mounted on the ferrule and including a 105 fixed arm and a movable arm, a crossbar carried by the fixed arm, co-operating means carried by the crossbar and movable arm for interlocking them, a follower mounted on the rod and the ends thereof adapted to 110 engage the fixed and movable arms, said follower including a sleeve for receiving the rod, plates mounted on said follower, said plates being outwardly curved at their lower ends for engaging over a mop, and means 115 screw threadedly engaging the rod for moving the follower toward the crossbar.

WILLIAM FETH.
